Inventor:
Frederick Joseph Otis.
By Archer Atton & Archer Atty's.

UNITED STATES PATENT OFFICE.

FREDERICK JOSEPH OTIS, OF APOLLONIA, WISCONSIN.

DESIGN FOR A STOVE-DOOR.

SPECIFICATION forming part of Design No. 28,097, dated December 28, 1897.

Application filed May 7, 1897. Serial No. 635,594. Term of patent 14 years.

To all whom it may concern:

Be it known that I, FREDERICK JOSEPH OTIS, a citizen of the United States, residing at Apollonia, county of Chippewa, and State of Wisconsin, have invented and produced a new and original Design for a Stove-Door, of which the following is a specification, reference being had to the accompanying drawing, which forms a part thereof.

10 The leading feature of my design consists of a stove-door of the form or outline and having thereon the configuration or decorations shown in the accompanying drawing and hereinafter described.

15 In the drawing, which represents a stove-door embodying my invention, A designates the door, having a plane central field B of a form substantially similar in outline to the

shape of the said door. Surrounding said field is a raised portion or bead C, parallel 20 with the edges of said door. Between said bead C and the edge D are the decorations E, consisting of raised scroll or convolute work, as shown.

Having now described my invention, what 25 I claim as new, and wish to protect by Letters Patent, is—

The design for a stove-door as herein shown and described.

In testimony whereof I have hereunto set 30 my hand this 2d day of April, 1897.

FREDERICK JOSEPH OTIS.
